[57] **CLAIM**

The ornamental design for a chemical truck mounted liquid tank, as shown and described.

DESCRIPTION

FIG. 1 is a top plan view of a chemical truck mounted liquid tank showing our new design;

FIG. 2 is a bottom plan view thereof;

FIG. 3 is a side elevational view thereof;

FIG. 4 is an opposite side elevational view thereof;

FIG. 5 is an end elevational view thereof, the opposite side being identical;

FIG. 6 is a perspective view thereof.

FIG.1

FIG.2
